UNITED STATES PATENT OFFICE

ROY H. SHERBONDY AND RAY E. SHERBONDY, OF AKRON, OHIO

DESIGN FOR A LAWN SPRINKLER

Application filed August 19, 1931. Serial No. 40,892. Term of patent 14 years.

To all whom it may concern:

Be it known that we, ROY H. SHERBONDY and RAY E. SHERBONDY, citizens of the United States, residing at Akron, in the county of Summit and State of Ohio, have invented a new, original, and ornamental Design for Lawn Sprinkler of which the following is a specification, reference being had to the accompanying drawing, forming part thereof—

The figure is a perspective view of a lawn sprinkler showing our new design.

We claim:

The ornamental design for a lawn sprinkler as shown.

Witness our hands this 1st day of August, A. D. 1931.

ROY H. SHERBONDY.
RAY E. SHERBONDY.
